UNITED STATES PATENT OFFICE.

AUSTIN M. DOBSON AND BLAIR L. DOBSON, OF ST. JOSEPH, MISSOURI.

ILLUMINATED ELECTRIC POSTER DEVICE.

1,317,436.

Specification of Letters Patent. Patented Sept. 30, 1919.

Application filed March 19, 1917. Serial No. 155,694.

To all whom it may concern:

Be it known that AUSTIN M. DOBSON and BLAIR L. DOBSON, citizens of the United States, residing at St. Joseph, in the county 5 of Buchanan and State of Missouri, have invented certain new and useful Improvements in Illuminated Electric Poster Devices, of which the following is a specification.

10 The object of our invention is to provide a clock which may be used to display advertising, either outdoors or indoors, the advertising being placed on a sectional ribbon and displayed as it slowly moves upward in front of a cabinet. The clock is also adapted to the display of a stationary sheet of advertising placed immediately back of a section of celluloid, or other transparent flexible substance inserted in the ribbon.

15 We accomplish our object by the mechanism illustrated in the accompanying drawings, in which:

Figure 1 is a front view of the clock and cabinet showing a blank for a transparent advertising sheet through a glass panel of the clock cabinet door;

20 Fig. 2 is a side sectional view of the clock case and the interior construction of the device showing the motor, the method of power transmission, the lengths of sectional advertising ribbon with a method of using a maximum and a minimum length, a drive roller, a gravity tension roller and its channel guides, a plurality of rollers and their 25 adjustments, a plurality of flanges on the rollers, supports for a stationary advertising sheet, a wiring and lighting system and connections, the arrangement of a translucent glass border around the cabinet door, a side 30 interior view of a removable head which contains the clock compartment, clock movement and adjustable bracket, a translucent glass dial, a weatherproof glass face and a side view of the removable front to the base 35 of the cabinet.

40 Fig. 3 is a front view showing the drive roller, the tension roller, its weight and a section of its guides, an adjustable roller and its adjustments to guide the ribbon and 45 a portion of the ribbon, also portions of 50 duplicate narrow belts with spacing connections, and flanges near the ends of the rollers which touch the back of the ribbon, also portions of duplicate narrow belts with 55 spacing connections, and flanges near the

ends of the rollers which touch the back of the ribbon K.

Fig. 4 is a view of the inside of the front door of the cabinet showing the illuminating system and reflectors, the wiring connections 60 and a translucent glass border and a clear glass panel in the cabinet door.

Fig. 5 is a plan view of the lower rollers showing the motive power, said translucent glass border and the illuminating system, 65 and flanges near the ends of the rollers which touch the back of the ribbon K.

Fig. 6 is a wire mesh cloth, metal hooks on the ends of two sections of the ribbon showing the method of connecting the sec- 70 tions, and

Fig. 7 is a detail drawing of the ribbon guide and the roller adjustment.

And Fig. 8 is a view similar to Fig. 2, showing a modification thereof in the 75 threading of the minimum amount of ribbon.

Similar letters refer to corresponding parts throughout the several views, the letter A indicating the clock cabinet and B 80 the clock. B¹ indicates a clock movement supported in cabinet A by an adjustable bracket C which is fastened at the sides of a dust-proof clock compartment D; this compartment is fastened to the roof of the 85 cabinet and has a hinged door D¹. D² represents three thumb screws by means of which the clock movement B¹ is adjusted to any angle or position on bracket C and is locked rigidly in place by means of an aux- 90 illiary bracket attachment D³ which is also fastened at the sides of compartment D. D⁴ is a translucent glass dial in front of which a removable, weather-proof, clear glass face D⁵ is placed, making the clock 95 accessible. D⁶ is a pane of glass which admits artificial light from the lighting system immediately below for the purpose of illuminating the translucent glass dial D⁴. We preferably use a clock which is electrically wound and regulated. D⁷ is a removable head and contains the clock B which is supported by pillars E E, which pillars are provided with a base E¹ having a removable front E² having fastenings e e. F indicates 105 a motor, G a drive roller and H H a plurality of pulleys. H¹ H¹ represent flexible transmission belts. I I represent suitable electrical wiring, and J J are rollers for carrying the ribbon. K is a section of rib- 110

bon and K^2 represents a blank or transparent section of ribbon K , as seen through the glass panel. L is a roller and L^1 is a weight; said roller and weight are by gravity variable in location from the upper to the lower rollers. Said weight roller also regulates the tension of ribbon K on the drive and other rollers. L^2L^2 are guide strips placed on the sides of the cabinet to form a channel at the ends of the tension roller L and its weight L^1 enabling them to move in proper alinement. Through the medium of said tension roller we are enabled to use a ribbon of varying lengths; the ribbon may be threaded in various ways. The diagram in Fig. 2 indicates the method of threading the maximum amount of ribbon K . In using the minimum amount of ribbon we preferably thread the same in the following manner: from front of drive roller G to front and over upper roller J^1 down to front and under tension roller L , up to front and over roller J^2 , down back of roller J^3 , front and down over J^4 , down back of and connecting under roller G , as shown in Fig. 8 by lines marked K^2K^1 . $M M$ are adjustable bearings upon which the axles of adjustable roller J^1 rest. M^1M^1 are flat metal strips hinged at their back ends and upon which adjustable bearings $M M$ rest. M^2M^2 are thumb screws upon the heads of which the movable ends of the flat metal strips M^1M^1 rest, thereby enabling thumb screws M^2M^2 to raise or lower either end of the adjustable roller J^1 , which guides ribbon K . $T T$ are cross rods located at the top and bottom and immediately back of the front section of ribbon K to support a stationary sign or poster, (not shown). U represents a compact electric lighting system consisting of a plurality of lamps $u u$ arranged on the back of door E . V is a flexible metal conduit by means of which current is supplied to the lamps. V^1 is a narrow translucent glass border placed at the top, bottom and sides and at right angles to the edges of the clear glass door panel A^1 which permits the exposed section of ribbon K (or K^1) to be artificially illuminated while concealing the lighting fixtures. $W W$ represent a plurality of metal reflectors. X is a narrow strip of wire mesh cloth fastened to one end of each section of ribbon, and X^1 is a narrow strip of

wire mesh cloth fastened to an adjoining end of another section of ribbon and provided with a plurality of small metal hooks X^2X^2 which hook into said wire mesh cloth X . $Y Y$ are narrow leather belts running the full length of and connected by a plurality of spacing connections to the side edges of sectional ribbon K . Y^2Y^2 are a plurality of short, flexible connections, one end fastened to the edge of ribbon K , the other end fastened to the face side of narrow leather belts $Y Y$. $Z Z$ are flanges located near both ends of each roller upon which the back of the ribbon K travels.

What we claim and desire to secure by Letters Patent, is:

1. The combination in an advertising device of the kind described having a driving mechanism, a plurality of rollers operated thereby, a sectional ribbon variable in length and carried continuously by said rollers, a special transparent section or sections inserted in said ribbon, duplicate narrow belts with spacing connections attached to said ribbon, wire mesh cloth ends with metal hooks for connecting the sections of said ribbon, supports for a stationary advertising sheet and a stationary advertising sheet adapted to be disclosed through a transparent section or sections in said ribbon. 70

2. In an advertising device of the kind described the combination of a driving mechanism and a sectional ribbon of variable length, an upper and a lower bank of rollers serving as conveyers for said ribbon, a driving roller for propelling the ribbon, a gravity tension roller, flanges near the ends of the rollers which touch the back of the ribbon, duplicate narrow belts with spacing connections attached to the side edges of said ribbon, flanges located between the ribbon and belts to hold the ribbon in alinement, thumb screws the heads of which support an adjustable plane with bearings resting thereon, and an adjustable roller with its axles resting on said movable bearings 80 to assist in guiding the ribbon. 85

In testimony whereof we affix our signatures in the presence of two witnesses.

AUSTIN M. DOBSON.
BLAIR L. DOBSON.
